UNITED STATES PATENT OFFICE.

CARL BREER, OF DETROIT, MICHIGAN.

INTERNAL-COMBUSTION-ENGINE MANIFOLD.

Application filed December 7, 1925. Serial No. 73,872.

It is the primary object of my invention to provide a simple and economical construction for controlling the heating of sections of an intake manifold by means of the 5 exhaust gases in the exhaust manifold.

With the above and other objects in view, my invention consists in the arrangement, combination and construction of the various parts of my improved device as described in 10 the specification, claimed in my claims and shown in the accompanying drawings, in which:

Fig. 1 is a side elevation of my improved device with certain parts thereof cut away.

15 Fig. 2 is a sectional view taken on line 2—2 of Fig. 1.

Fig. 3 is a sectional view taken on line 3—3 of Fig. 1.

I have shown a manifold construction comprising an exhaust section indicated generally as 5, and an intake section indicated generally as 6. The exhaust section has portions 7 connecting it with the engine cylinders and the intake section has portions 8 connecting 25 it with the engine cylinders. A fuel passageway 9 leading from a conventional carburetor (not shown) attaches to the central portion of the intake manifold as at 10.

The exhaust and intake sections of the 30 manifold are separate except at their central portions where they are cast integral as indicated generally at 11.

The exhaust gases from the internal combustion engine to which the manifold is attached normally pass through the passages 35 7 and passageway 12 past the valve 13 and cut through the exhaust pipe 14. The valve 13 is mounted on a rod 15 extending through the exhaust manifold adjacent its connection 40 with the exhaust pipe 14. One end of the rod 15 is mounted in a removable section 16 of the exhaust manifold, such section being bolted to the remainder of the manifold by means of bolts 17, so as to permit assembly 45 and disassembly of the valve mechanism through the aperture covered by the section 16. A rounded valve 18 is also mounted on the rod 15 and is so positioned as to close the side passage 19 of the exhaust manifold 50 when the valve 13 is in position to open the passage 12. A handle 20 is provided upon one end of the rod 15 and a suitable rod or other extension may be attached thereto for manually operating the valve mechanism 55 from a remote point.

It will be noted that in the normal functioning of the exhaust manifold a small percentage of the exhaust gases may impinge upon the outside of the passage 21 of the intake manifold but owing to the fact that 60 the passage 19, during such normal operation, is closed, the exhaust gases will tend to quickly pass through the passage 12 and the exhaust pipe 14 to the muffler with a very small resultant heating of the intake passage. When it is desired to impart a 65 considerable heat to the intake passage as in warming up the internal combustion engine, particularly in cold weather, the lever 20 may be operated to cause the valve 13 to close the passage 12 and the valve 18 to open the passage 19 so that none of the exhaust gases may pass through the exhaust pipe 14 from the passage 12 but all of them must pass around the intake passage 21 and out through the reduced opening 22 into the 70 passage 19 and thence through the passage 23 into the exhaust pipe 14 with the consequent result that a much greater play of the 75 exhaust gases upon the intake passage will be had and the intake passage with its contained fuel will be heated to a much higher 80 degree than in normal operation.

It will be obvious that various changes 85 may be made in the arrangement, combination and construction of the various parts of my improved device without departing from the spirit of my invention and it is my intention to cover by my claims such changes as may be reasonably included 90 within the scope thereof.

What I claim is:

1. Manifolding for internal combustion engines comprising an intake manifold having a central fuel entrance portion and diverging arms, an exhaust manifold having a central portion at least partially surrounding the central portion of the intake manifold and diverging arms separated from the intake arms, one of the arms of the exhaust manifold having integrally cast and co-extensive therewith a portion forming a smaller passage than the passage in the arm, said smaller passage and the passage in the arm having a common wall, said smaller passage communicating with the central portion, and a combination valve having portions extended into both passages and adapted, when operated, to alternately close one and open the other passage.

2. Manifolding for internal combustion engines comprising an intake manifold having a central fuel entrance portion and diverging arms, an exhaust manifold having a central portion at least partially surrounding the central portion of the intake manifold and diverging arms separated from the intake arms, one of the arms of the exhaust manifold having integrally cast and co-extensive therewith a portion forming a smaller passage than the passage in the arm, said smaller passage communicating with the central portion, a combination valve having portions extended into both passages and adapted, when operated, to alternately close one and open the other passage, and baffling in the central portion of the exhaust manifold normally tending to direct the exhaust gases through the larger passage, but permitting the same to pass thru the smaller passage when the larger passage is closed.

3. Manifolding for internal combustion engines comprising an intake manifold having a central fuel entrance portion and di-

verging arms, an exhaust manifold having a central portion at least partially surrounding the central portion of the intake manifold and diverging arms separated from the intake arms, one of the arms of the exhaust manifold having integrally cast and co-extensive therewith a portion forming a smaller passage than the passage in the arm, said smaller passage communicating with the central portion, a combination valve having portions extended into both passages and adapted, when operated, to alternately close one and open the other passage, and baffling in the central portion of the exhaust manifold normally directing exhaust gases away from a portion of the enclosed central portion of the intake manifold when the larger passage is open but permitting the gases to pass around all of the enclosed portion thereof and out thru the smaller passage when the larger passage is closed.

CARL BREER.
